UNITED STATES PATENT OFFICE.

ABRAHAM B. PROBASCO, OF LEBANON, OHIO.

DESIGN FOR AN ARM MEMBER FOR REELS.

SPECIFICATION forming part of Design No. 33,507, dated November 6, 1900.

Application filed June 13, 1900. Serial No. 20,215. Term of patent 7 years.

To all whom it may concern:

Be it known that I, ABRAHAM B. PROBASCO, a citizen of the United States, and a resident of Lebanon, Warren county, State of Ohio, 5 have invented and produced a certain new and original Design for the Arm Member of a Reel; and I do declare that the following is a description thereof sufficiently clear, full, and exact to enable others skilled in the art 10 to which it appertains to make and use the same, attention being called to the accompanying drawing, with the reference-numerals marked thereon, which forms also a part of this specification.

15 This invention relates to the arm member of reels; and the object is to increase the usefulness of such members, as well as to improve and enhance their appearance, by certain novel and pleasing effects obtained by a 20 peculiar arrangement, shape, and outline, all as hereinafter described, and illustrated in the accompanying drawing, which shows in

perspective view the arm member of a reel embodied with the design contemplated by my invention.

25

My design consists of having these members formed of two parts arranged in a vertical plane, one below the other, and disposed to each other at an angle the apex of which is at the extreme outer end of said arm member where the two parts thereof join each other. From this point these parts diverge until they reach a central upright from which they radiate.

30

Having described my invention, I claim the 35 same as follows:

The design for the arm member of a reel substantially as shown and herein described.

In testimony whereof I hereunto set my hand in the presence of two witnesses.

ABRAHAM B. PROBASCO.

Witnesses:

C. SPENGEL,
ARTHUR KLINE.
